UNITED STATES PATENT OFFICE.

AUGUST HENRIKSSON, OF GOTENBORG, SWEDEN.

ELECTRIC STEAM BOILER.

Application filed December 11, 1923, Serial No. 680,002, and in Sweden December 12, 1922.

The present invention relates to electric steam boilers of the kind in which the heating is effected by one or more electrodes arranged in the boiler and the water serving 5 as a resistance for the heating of the same.

For increasing the output of the boiler, there has been proposed to alter the concentration of the salt in the water, since the conductivity of the water within certain 10 limits is increased with increased salt concentration.

These proceedings have proven to be uneconomical in the use of boilers of the construction heretofore known, since the reducing 15 of the salt concentration of the water has necessitated the removing from the boiler of a comparatively great portion of the total volume of the water.

The invention has for its main object to 20 overcome this inconvenience and with this and other objects in view, the invention will be hereinafter described with reference to the accompanying drawings showing diametrically some embodiments of the invention.

In the drawings:

Figure 1 is a vertical section of the steam boiler according to one embodiment;

Figure 2 is a horizontal section of the 30 same boiler;

Figure 3 is a vertical section;

Figure 4 is a horizontal section of the steam boiler according to a second embodiment;

Figures 5 and 6 are similar views of a 35 steam boiler according to a third embodiment; and,

Figure 7 is a vertical section of an automatic valve.

Referring to the embodiment illustrated 40 in Figures 1 and 2, 1 denotes a vertical cylindrical boiler. In compliance with this invention, there is arranged in the upper portion of the boiler, a receptacle or chamber 2, from which depends three tubes 3 tapering in the direction downwards and closed at their lower ends. The tubes at 45 their lower ends communicate with a pipe 4, whereas the upper ends communicate with the receptacle 2. The numeral 5 indicates electrodes provided in the tubes 3 and electrically connected with the conductors 6. The electrodes 5 are surrounded by insulating 50 members 7 in the form of tubes of porcelain or other suitable material, placed within the tubes 3. The feed water is applied

into the pipe 4 through the pipe connection 8 by means of a centrifugal pump 9. The water space of the boiler 1 is, by means of pipes 10 and 4 connected with the interior 60 of the tubes 3. From the steam space of the receptacle 2, a pipe 11 leads whereby the steam generated may be carried adjacent the bottom of the boiler 1. The steam enters the water of the boiler through a set 65 of nozzles 12 and ascends through the water into the steam space of the boiler, from which the steam is discharged through a conduit 13. The water space of the boiler 1 furthermore, through a pipe connection 70 14, communicates with the feed water piping 8 on the suction side of the pump 9. The numeral 15 denotes a discharge pipe for the water in the boiler 1.

The pipe connections 8, 10, 14, and 15 75 are each provided with a regulating valve 16, 17, 18 and 19 respectively and by preference, work automatically. Such automatic valves may be of the construction shown in Figure 7.

In the Figure 7 of the drawings, 20 denotes the valve proper, having the spindle 21 connected with a piston 23 movable within a cylinder 22. The lower portion of this cylinder 22 is, by means of a channel 24, connected with a fluid pressure pipe 25 and by means of a channel 26, with a discharge pipe 27. The upper portion of the cylinder 22 is, by means of channels 28 and 29, connected with the pressure and discharge pipes 80 respectively. By means of a valve 31 controlling the pressure pipe 25 and actuated upon by an electro-magnet 30, the pressure medium is permitted to enter into the cylinder, either through the channel 24 or 28, 85 whereby the piston 23 is moved so as to shut or open the valve 20. The electro-magnet 30 simultaneously actuates the valve 32 adapted to put either the channel 26 or 29 in connection with the discharge pipe 27, 90 thus allowing the pressure medium to escape from the side of the piston 23, which for the occasion is not in connection with the pressure pipe 25.

The different electro-magnets of the 95 valves are controlled automatically by the water levels and steam pressure in the boiler in the following manner:

In the electrical circuit including the electro-magnet of the valve 16 of the water feed piping, there is arranged a circuit closing device 33, which causes the valve to open 110

when the water level within the chamber 2 drops below a certain level.

The electro-magnet of the valve 17 in the pipe connection 10 is included in an electrical circuit, which may be closed by a device influenced by the pressure in the boiler, for instance, a pressure gauge 34, so that the valve 17 is opened when the steam pressure in the boiler has been raised to a predetermined degree.

The pressure gauge 34 is also adapted to close a circuit to the electro-magnet of the valve 18, when the pressure in the boiler has been reduced to a certain degree, whereby the valve 18 becomes opened.

The electro-magnet of the valve 19 is arranged in a circuit in which there is included a circuit closing device 35 influenced by the water level in the boiler 1, so that the valve 19 is opened when the water level exceeds a certain maximum.

The operation of the electric steam boiler above described is as follows:

After water has been supplied to the water space of the boiler 1 to the level shown, the electric current is supplied to the electrodes 5. By the resistance of the water, the latter is heated, whereby steam is produced in the tubes 3, and arises to the steam space of the receptacle 2, from which the steam, through the pipe 11, is conducted down into the water space of the boiler 1. The arising steam heats the water in the boiler 1 and finally, it is discharged through the pipe 13. Provided the feed water contains a certain quantity of salt as is the case when undistilled water is used, the salt concentration of the water in the tubes 3 and the receptacle is augmented in the same degree as steam is produced, whereby the conductivity of the water and consequently the steam generation, is increased. When the steam generation exceeds the steam consumption, the steam pressure in the steam boiler is increased. At a certain steam pressure, the pressure gauge 34 closes the circuit of the valve 17 in the pipe connection 10 so that the said valve is opened. On account of the resistance offered by the nozzles 12, a higher steam pressure will be presented in the receptacle 2 than in the boiler proper. By this pressure difference, the salt-containing water from the steam generator 2 and tubes 3 will be discharged through the pipe 10 into the boiler 1. When the water level in the steam generator has been lowered to a certain point, the contact device 33 becomes operative, so that the feeding valve 16 is opened. Thus, the salt concentration in the steam generator 2 and tubes 3 is reduced and the electric conductivity lowered so that the steam generation is diminished. If the steam pressure in the boiler should fall below a certain value, the pressure gauge 34 will close the

circuit to the valve 18 so that salt-containing water from the boiler 1 is permitted to enter into the feed piping 8 on the suction side of the pump 9. Now, water with comparatively high salt-concentration will be fed into the steam-generator, and as a consequence, the steam generation will be increased.

Due to the relatively small water space of the steam generator and its communication with the boiler proper above described, the alteration of the salt-concentration in the steam-generator is effected rapidly and the loss of hot water is greatly reduced.

It is not necessary that the valves 16, 17, 18 and 19 be provided so as to operate automatically, they may be arranged to be manually operated, if so desired.

The valves 17 and 18 also may be regulated automatically, by means of suitable devices, with respect to the consumption of electric power, in such a manner that the said consumption is held between certain maximum and minimum limits.

The embodiment of the invention shown in Figures 3 and 4, which is intended to be used for comparatively lower electric tensions, differs from the embodiment previously described in that the electrodes 5 comprise flattened rods fitted in the tubes 3 and cooperating each with a contra-electrode 5^a insulated from the electrodes 5, and of the same shape as the latter.

In the embodiment illustrated in Figures 5 and 6, which is adapted to be used for high electric tensions, the steam-generator receptacle 2 and the tubes 3 communicate with a receptacle 2^a placed on the bottom of the boiler 1. By means of a pipe connection 4^a and a circulating pump 36, the water from the receptacle 2^a is caused to be sprayed downwardly by the strainers 37, to the electrodes 5 in the tubes 3. In this construction, the strainers 37 serve as contra-electrodes.

The remaining details in this embodiment of the invention, in all essential points, correspond with details described in connection with the Figures 1 and 2, and are indicated by corresponding reference characters; accordingly, a particular description thereof is unnecessary.

It is of course understood that the invention is not confined to the embodiments thereof described and shown in the drawings, but which come within the scope of the appended claims, for instance, the steam generator or chamber 2 may be arranged exteriorly of the boiler instead of being arranged within the boiler as disclosed in the drawings.

I claim:

1. An electric steam generator comprising a boiler, a steam generating chamber of a small size in relation to said boiler, elec-

- trodes arranged within said chamber, a water feed piping connected to said chamber, means of communication between the steam space of said chamber and the water space of said boiler whereby the transmission of steam generated may be effected there between and means whereby the transmission of water may be effected between said boiler and chamber.
- 10 2. An electric steam generator comprising a boiler, a steam generating chamber of a small size in relation to said boiler, electrodes arranged within said chamber, a water feed piping connected to said chamber and boiler, means of communication between said boiler and chamber whereby the transmission of water may be effected there between and means of communication between the steam space of said chamber and the water space of said boiler whereby the steam generated in said chamber will be caused to pass through the water of said boiler.
- 15 3. An electric steam generator comprising a boiler, a steam generating chamber of a small size in relation to said boiler, electrodes arranged within said chamber, means of communication between the steam space of said chamber and the water space of said boiler, a pipe connection between the water space of said chamber and said boiler, and regulating means in said pipe connection adapted to regulate the water supply from said chamber to said boiler.
- 20 4. An electric steam generator comprising a boiler, a steam generating chamber of a small size in relation to said boiler, electrodes arranged in said chamber, a steam pipe leading from the upper end of said chamber and communicating with the lower end of said boiler, a pipe connection between the water space of said boiler and the lower end of said chamber, and regulating means in said pipe connection adapted to regulate the water supply from said boiler to said chamber.
- 25 5. An electric steam generator comprising a boiler, a steam generating chamber of a small size in relation to said boiler, electrodes arranged in said chamber, a water feed piping communicating with said chamber and boiler, a pipe connection between said boiler and said water feed piping, and regulating means in said pipe connection adapted to regulate the water supply from said boiler to said chamber.
- 30 6. An electric steam generator comprising a boiler, a steam generating chamber of a small size in relation to said boiler, electrodes arranged in said chamber, a water feed piping connected to said chamber, a pipe connection between the water space of said chamber and said boiler, and regulating means in said pipe connection adapted to be controlled by the steam pressure in the boiler, whereby to automatically control the flow of water from said chamber into said boiler when the steam pressure has attained a certain degree.
- 35 7. An electric steam generator comprising a boiler, a steam generating chamber of a small size in relation to said boiler, electrodes arranged in said chamber, a water feed piping connected to said chamber, a pipe connection between the water space of said boiler and said chamber, and regulating means in said pipe connection adapted to be actuated by the steam pressure in said boiler so as to automatically allow water to pass from said boiler into said chamber when the pressure has been reduced to a certain degree.
- 40 8. An electric steam generator comprising a boiler having a water space in its lower end and a steam space in its upper end, a steam generating chamber of a relatively small size arranged within the steam space of said boiler, a plurality of tubes communicating with and depending from said chamber, an electrode arranged within each tube, water feed piping communicating with said chamber, boiler and lower ends of said tubes, and means of communication between said chamber and boiler whereby the steam generated may pass therebetween.
- 45 9. An electric steam generator comprising a boiler having a water space in its lower portion and a steam space in its upper portion, a steam generating chamber arranged within said boiler, electrodes arranged within said chamber, water feed piping communicating with the lower end of said chamber and the water space of said boiler, a steam pipe leading from the steam space of said chamber and communicating with the water space of said boiler, and a steam outlet pipe leading from the steam space of said boiler whereby the steam generated within said chamber will be caused to pass through the water within said boiler before passing through said outlet pipe.
- 50 10 In witness whereof I have hereunto set my hand.

AUGUST HENRIKSSON.
